UNITED STATES PATENT OFFICE.

LEWIS F. FALES, OF WALPOLE, MASSACHUSETTS.

SEWING-MACHINE.

No. 925,320.

Specification of Letters Patent.

Patented June 15, 1908.

Application filed March 5, 1908. Serial No. 419,262.

To all whom it may concern:

Be it known that I, LEWIS F. FALES, a citizen of the United States, residing in Walpole, in the county of Norfolk and State 5 of Massachusetts, have invented an Improvement in Sewing-Machines, of which the following description, in connection with the accompanying drawings, is a specification, like letters on the drawings representing like 10 parts.

The present invention relates to a sewing machine, and is embodied in what is known as a double-looped stitch machine, (the "Grover and Baker") the invention being 15 particularly adapted to a machine of this type provided with multiple needles for sewing a number of rows of stitches at the same time.

In a machine of the Grover and Baker 20 type, a hook oscillating on a vertical axis is utilized, the said hook encircling the needle in the formation of the stitch, and it is necessary that the inner periphery of the said hook should be in substantially the 25 same position with relation to the needle during both the up and down strokes of the latter in the formation of the stitch. Furthermore, it is desirable, especially in a multiple needle machine, where a large amount 30 of material is being handled, to utilize a continuous feed, in which case the needle must be moved laterally during the formation of the stitch. Consequently, a lateral movement of the hook, corresponding to 35 that of the needle, must be provided for, in order that the point of the hook may pass close to the side of the needle in both the up and down strokes thereof.

In accordance with the invention, the 40 needle bar or needle bars, each of which may be provided with more than one needle, if necessary or desirable, is vertically movable in a pivotally supported bearing and operated by an eccentric, so that both reciprocating and rocking movements are produced, the reciprocating movement causing the formation of the stitch, while the rocking movement provides for the lateral movement of the needle to follow the material as 45 it is fed along. The oscillating hook which cooperates with the needle in the formation of the stitch is also arranged to move laterally with the lateral movement of the needle, the said hook being capable of rotation or oscillation in bearings formed in a

pivotally supported member below the work-supporting plate and provided with suitable actuating mechanisms. The hook member is so arranged with relation to its actuating mechanism that it can be tipped forward 60 from under the bed-plate, in order to render it accessible for threading, or other purposes.

Figure 1 is a front elevation of a sufficient portion of a sewing machine to illustrate the 65 invention; Fig. 2 is a side elevation, partly broken away, looking toward the left of Fig. 1; Fig. 3 is a vertical section, on an enlarged scale, taken on line x^3 of Fig. 1; and Fig. 4 is a horizontal section, on line x^4 70 of Fig. 3; and Fig. 5 is an enlarged perspective view of one of the fastening studs for the hook members.

The needle bars a , of which there may be any number desired, are shown as each provided with three needles a^2 , it being immaterial, of course, except as a matter of convenience, how many needles are carried by each bar. The needles a^2 coöperate in the formation of the stitch with the oscillating 80 hooks b , each of which is shown as rotatably mounted in vertical bearings b^2 in a pivoted holder b^3 , the said holder being shown as having a rearwardly projecting arm b^4 pivoted at A^2 in a portion of the frame A . 85

The vertical movement of the needle bars a to perforate the material and form the stitches therein is provided for by means of eccentrics B^2 mounted on the main driving shaft B , and, in order that the needle may 90 travel with the material in the feed movement thereof, the arrangement is such that the needle, while perforating the material, will move laterally, as well as longitudinally, during the formation of the stitch. 95 For this purpose, the needle bar is provided with a bearing in a member c which is pivotally supported at c^2 on the frame of the machine, the eccentric being so adjusted and arranged as to cause a lateral movement at 100 the upper end of the needle bar, as well as the longitudinal movement already described. The relation between the pivotal support of the member c in which the needle bar bears and the axis of the eccentric is 105 such that, in the movement of the eccentric, the member c will be oscillated in its bearing, so that a lateral, as well as a longitudinal movement of the needle itself will be produced as the eccentric rotates.

The hooks b are arranged to follow the lateral movement of the needles during the formation of the stitch, so that the inner peripheries of the hooks will lie close to the needle throughout the entire operation. For this purpose, the pivoted holder b^3 is arranged to be rocked on its pivotal support at A^2 through the agency of an arm d which is connected with a radial projection d^2 from a rock shaft d^3 which is arranged to be oscillated in the operation of the machine. In the construction shown, the rock shaft d^3 is provided with an arm d^4 connected by means of a link d^5 with an eccentric strap d^6 which coöperates with an eccentric B^3 upon the main driving shaft B .

For the purpose of balancing the machine, the needle bars a are arranged to reciprocate alternately, the eccentrics B^2 being, as shown, oppositely disposed to each other. For this reason, the sets of hooks coöperating with the needles must be separately operated, the mechanism provided for this purpose being best shown in Fig. 1. It is necessary, in the formation of the stitch, that the hooks b should be oscillated, and, for this purpose, each hook is provided with a pinion b^7 at the lower end, the said pinion meshing with a rack b^8 which is arranged to be reciprocated through the action of an elbow lever b^9 pivoted at b^8 and operated by a cam b^9 , which is shown as connected to a countershaft b^{10} . The said countershaft is driven from the main shaft B through the agency of bevel gears B^4 and b^{12} . The rack b^8 above described moves back and forth during the rotation of the cam b^9 , thus oscillating the hooks b throughout the series. The other sets of hooks are made longer than those previously described and provided with pinions b^{20} arranged to coöperate with a rack b^{20} , the construction and operation of which is the same as that of the rack b^8 , except that the two racks reciprocate in opposite directions, one moving in one direction while the other moves in the other.

While only two sets of needles are herein shown, it is obvious that any number of sets desired may be extended across the machine, the two racks b^8 and b^{20} coöperating respectively with all the hooks belonging to all the needles which operate at the same time. The mechanism for producing the lateral movement of the hooks is also duplicated, as best shown in Fig. 2, there being an arm d^{10} corresponding to the arm d^4 which operates the arm d^{20} , the two arms d^2 and d^{20} swinging in opposite directions, in order to have the movement of the hooks correspond with that of the needles.

For the purpose of rendering the hooks accessible for threading, or other purposes, the hook-carrying members b^3 are arranged to be easily disconnected from the actuating

devices d , so that they can be rocked on their pivotal supports until the hooks themselves are moved out from under the work-supporting table C , as shown in dotted lines, Fig. 3. In the construction shown, the arms d are arranged to hook over the rods or pins b^{13} , supported in lugs formed on the hook-supporting members and are provided with finger pieces d^{10} by which they can be easily lifted to release the said members. In order that the means for producing the oscillation of the hooks may not interfere with the operation above described, or with the lateral movement of the hooks in the operation of the machine, the racks b^6 and b^{20} are shown as cut on the arcs of circles struck from the pivotal axes A^2 and A^{20} of the members b^3 and b^{20} , respectively, so that as either of the said members is rocked upon its pivotal support, the pinions will slide along the face of the rack which is operating, without coming out of mesh.

For the purpose of adjusting the initial position of the hooks relative to the needles, the studs b^{12} are eccentrically supported with relation to the lugs, so that by turning said studs the lateral position of the hooks can be slightly varied. This variation in position is best indicated in dotted lines, Figs. 3 and 4. As shown in Fig. 5, the end of the stud is screw threaded in the lug, and the engaging portion thereof is smaller in diameter than the said end and is eccentric thereto. The stud is also shown as provided with a screw driver slot for turning the stud to adjust the same.

Claims.

1. In a sewing machine, the combination with a needle bar provided with a needle; of means for producing longitudinal and lateral movements of said needle bar; a hook adapted to oscillate around the needle on an axis substantially parallel to the axis of the needle bar; a pivotally supported bearing member for said hook; an actuating device connected with said supporting member to produce an oscillating movement thereof; and means for disconnecting said actuating device from said member, substantially as described.

2. In a sewing machine, the combination with a laterally movable needle; of a hook arranged to oscillate around the needle on an axis substantially parallel to the axis of the needle; a pivotally supported bearing member for said hook; a reciprocating member; and means for detachably securing said bearing member to said reciprocating member, whereby the said bearing member is oscillated during the operation of the machine and may be disconnected to render the hook accessible, substantially as described.

3. In a sewing machine, the combination with a laterally movable needle; of an oscil-

lating hook the axis of which is substantially parallel to the needle; means for producing a lateral movement of said hook to correspond to that of the needle; a pinion 5 connected with said hook; and a reciprocating rack coöperating with said pinion to oscillate said hook.

4. In a sewing machine, the combination with a needle; of means for producing a 10 lateral movement thereof in the formation of a stitch; a hook coöperating with said needle; a pivotally supported bearing member for said hook; a reciprocating device connected with said bearing member to produce a lateral movement of the hook; a pinion 15 connected with the hook; and a reciprocating rack coöperating with said pinion and having its face curved on an arc struck from said pivotal support as a center.

20 5. In a multiple needle sewing machine, a series of needle-bars each provided with a plurality of needles, so arranged as to reciprocate alternately; a plurality of hooks to coöperate with each bar a pinion connected with each hook; means for producing lateral movements of said hooks and 25 bars in unison; reciprocating racks coöperating with said pinions to rotate said hooks;

and means for alternately reciprocating said racks.

6. The combination with a plurality of laterally movable needles; of laterally movable oscillating hooks surrounding said needles and to coöperate therewith in forming stitches; means for laterally adjusting 30 said hooks with relation to said needles; pinions connected with said hooks, and a reciprocating rack engaging a plurality of 35 said pinions.

7. In a sewing machine, a plurality of 40 needles formed in groups; means for reciprocating said groups of needles alternately; hooks arranged in corresponding groups, said hooks surrounding the needles and oscillating on axes substantially in line 45 with the needles; gears connected with said hooks; and alternately reciprocating racks meshing with said gears.

In testimony whereof, I have signed my name to this specification in the presence of 50 two subscribing witnesses.
